UNITED STATES PATENT OFFICE.

JAMES F. WINCHELL, OF SPRINGFIELD, OHIO.

HOOD FOR FORGES.

SPECIFICATION forming part of Letters Patent No. 297,901, dated April 29, 1884.

Application filed September 7, 1883. (No model.)

To all whom it may concern:

Be it known that I, JAMES F. WINCHELL, a citizen of the United States, resident at Springfield, in the county of Clark and State of Ohio, 5 have invented certain new and useful Improvements in Hoods for Forges; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of an end elevation of the forge with the hood in place. Fig. 2 is a sectional view of the hood removed.

This invention has relation to hoods for portable forges; and it consists in the construction and novel arrangement of a door for the hood, as will be hereinafter fully described, and particularly pointed out in the claim appended.

Referring by letter to the accompanying drawings, *a* designates the top plate of the forge, which is mounted on suitable legs, and is provided with any of the known mechanisms for driving the fan. The top plate or fire-pot is bowl shape in this instance, and the 20 hood *e* is bolted to its rim, the base of the hood being similar in shape to the rim of the bowl. The top of the hood is conical in form.

a' designates the door-space, and *b* the flue leading from the hood. The door *g* is in the

form of a section of a hollow cylinder, having 35 a section of a hollow cone top surmounted by a conical cap-ring, *b'*, which rests upon the conical top *c* of the hood around and below the flue *b*.

f designates the handle of the door. The 40 door extends down the side of the hood and overlaps the flange *h* below the door-space *a'*, but does not reach the groove formed between the rim of the fire-pot and the hood. The door does not therefore slide in the groove, 45 which is liable to be obstructed by coal dust and ashes, but swings around above it.

The cap-ring *b'* is not likely to be burned out, as hinges are, being farther from the fire and on the outside of the hood. 50

A hood of this construction is very convenient for use where articles are to be melted, as it prevents the fumes from escaping into the room, and when not needed it may be swung around out of the way. 55

Having thus fully described my invention, what I claim as new, and desire to secure by Letters Patent, is—

In a forge, the combination, with a hood having a door-space and a conical top, of a 60 revolving door supported on the hood-top by a cap-ring, substantially as specified.

In testimony whereof I affix my signature in presence of two witnesses.

JAMES F. WINCHELL.
